REMOVAL OF COPPER AND NICKEL FROM
FATTY ACIDSJoseph W. Opie, Minneapolis, Minn., assignor to General
Mills, Inc., a corporation of DelawareNo Drawing. Application June 20, 1951,
Serial No. 232,657

6 Claims. (Cl. 210—41)

Saturated fatty acids are frequently prepared from unsaturated fatty acids by a hydrogenation procedure in which metallic catalysts (usually nickel in some form) are used. In this procedure and in other processing steps the fatty acids may also come in contact with metals such as copper, in valves, transfer lines, pumps, and other pieces of equipment. Copper and nickel soaps can thus be formed and will be contained in the raw undistilled acid. For some uses the saturated acids are first subjected to distillation and as a result the metals remain behind in the residue. For some uses for fatty acids, however, the cost of distillation is prohibitive. For these uses it is necessary to remove traces of metal, particularly copper and nickel, by other means.

It is known that treatment of fatty acids with mineral acids to remove color, metal and the like, has been used before. In these instances, however, it has been necessary to wash the treated acids with water or to distill them or subject them to some other treatment in order to remove the mineral acid. These additional steps are slow and in some instances expensive.

It has now been found possible to remove copper and nickel from saturated fatty acids without the necessity of resorting to distillation and without the necessity of cumbersome operations, such as water washing, and the like.

It is therefore an object of the present invention to provide a novel process of removing copper and nickel from fatty acids by a process which does not require distillation of the fatty acids, and which does not require water washing.

The present invention involves the treatment of saturated fatty acids with bleaching clay in the presence of a strong mineral acid. A wide variety of bleaching clays may be employed. Typical of these are the bleaching clays of the montmorillonite type, such as Pike's Peak bleaching clay No. 9077. The bleaching clay is usually employed in a quantity of from 1% to 3%, preferably about 2%, although larger quantities may be used but are usually found unnecessary. The quantity of strong mineral acid employed may vary from 0.1% to 1% and preferably about 0.5%. The strong mineral acid and the bleaching clay may be mixed with the fatty acids in any order but must be present simultaneously in the treatment. Instead of adding the acid and clay separately, it is possible to add the acid to the clay and then add the acid-containing clay to the fatty acid.

During the treatment no particular temperature is necessary, but the saturated fatty acids should be in a liquid condition for intimate contact with the clay and acid. Temperatures of around 185° F. have been found to be satisfactory.

The time of treatment may be varied widely depending upon the results desired. As will be seen from data

2

given hereinafter, it will be found that treatment periods of even less than one minute are effective for partial reduction in the quantity of copper and nickel. Usually a minimum of about 3 minutes is desirable. It is usually not necessary to extend the treatment period beyond about 20 minutes in order to obtain excellent copper and nickel removal.

A particular advantage of the present invention is the fact that the process results in the removal of the copper and nickel without the deposit of any residual mineral acid in the fatty acids. As long as the quantity of mineral acid is maintained not in excess of 1%, it is found that the mineral acid is retained by the clay and is removed when the clay is filtered off. The fatty acids thus treated are immediately available without further processing for use in the arts in which undistilled fatty acid may be employed.

In the following examples the copper analysis reported is actually the total of copper and nickel inasmuch as the method employed for analysis (U. S. Rubber Company's sodium diethyldithiocarbamate method) determines the total of these metals.

Example 1

150 grams of a mixture of fatty acids containing approximately 55% palmitic acid and 45% stearic acid were heated to 185° C. and stirred. To this was added 0.88 g. of 85% phosphoric acid and 3 g. of a montmorillonite bleaching clay (Pike's Peak No. 9077). The mixture was stirred for 20 minutes and then filtered. The untreated acids employed as a starting material contained 3.2×10^{-3} % of copper, while the treated product obtained contained 3.7×10^{-4} % of copper. No free mineral acid was present in the treated product.

Example 2

Several mixtures of fatty acids having approximately the same composition as that described in Example 1, each of the samples, however, having different percentages of copper, were treated according to the process described in Example 1, and were analyzed for copper after treatment. The results are indicated in the following table:

Percent Copper Before Treatment	Percent Copper After Treatment	Percent Mineral Acid
2.6×10^{-3}	1.7×10^{-4}	None.
3×10^{-3}	2.0×10^{-4}	None.
2.2×10^{-3}	1.5×10^{-4}	None.

Example 3

The process previously described was carried out continuously on a pilot plant scale. Fatty acid from storage was continuously fed to a mixing kettle at a rate of 2.76 pounds per minute. An acid activated montmorillonite clay (Super Filtrol FO) was added at a rate of 0.0552 pound per minute and phosphoric acid was fed at a rate of 0.01623 pound 85% H_3PO_4 per minute. The discharge from the kettle was regulated such that the average residence time in the kettle was 5 minutes. The mixture withdrawn was filtered and the fatty acid was fed to a flaking roll. Samples were collected from the outlet, from the filter press and from the flaking rolls at 30 minute intervals. These were mixed into two composite samples which were analyzed for copper. A sample was

also taken from the storage kettle and analyzed for copper. The results of these analyses are as follows:

	Percent Copper	Percent Mineral Acid
Sample from storage.....	2.9×10^{-3}	
Composite from filter.....	5×10^{-5}	None
Composite from flaker.....	6.6×10^{-5}	None

It is thus apparent that the present process may readily be conducted on a continuous basis.

Example 4

A mixture of fatty acids of approximately the same composition as those described in Example 1, and having a copper content of $2.9 \times 10^{-3}\%$ was heated to 185° F. It was stirred and treated with 0.5% by weight of hydrochloric acid (2.3 cc. of 37% acid having a S. G. of 1.18 at 60° F.). 2% by weight of Super Filtral FO was added and the mixture was heated and stirred for 15 minutes. It was then filtered and the filtered product was analyzed for copper. It was found to contain $5.9 \times 10^{-5}\%$. No mineral acid remained in the product.

Example 5

The untreated mixed fatty acids of the preceding example were treated with 0.5% by weight of phosphoric acid (0.6% of 85% acid) and 2% by weight of Super Filtral FO at 185° F. Samples were removed at the end of $\frac{3}{4}$ min., $1\frac{1}{2}$ min., 3 min., 5 min., 10 min., and 20 min. The results of the variation in time of treatment are shown in the following table:

	Copper content
Untreated material.....	2.9×10^{-3}
After $\frac{3}{4}$ minute treatment.....	2.6×10^{-3}
After $1\frac{1}{2}$ minute treatment.....	1.8×10^{-3}
After 3 minute treatment.....	3.2×10^{-4}
After 5 minute treatment.....	1.8×10^{-4}
After 10 minute treatment.....	1.6×10^{-4}
After 20 minute treatment.....	7×10^{-5}

It is apparent, therefore, that even on extremely short periods of contact some removal of copper is obtained, and the time required for removal of copper to a very low level is not very extended.

Example 6

The effect of varying concentrations of acid is indicated by the present example in which mixed fatty acids containing approximately 55% palmitic and 45% stearic acids and having $3.4 \times 10^{-3}\%$ of copper were treated with 2% of bleaching clay and with 0.1%, 0.25% and 0.5% of phosphoric acid. The results are indicated by the following table:

Material	Copper Content, percent
Untreated material.....	3.4×10^{-3}
Untreated material, 2% clay and 0.1% phosphoric acid.....	2.8×10^{-3}
Untreated material, 2% clay and .25% phosphoric acid.....	7.9×10^{-4}
Untreated material, 2% clay and .5% phosphoric acid.....	1.8×10^{-4}

Example 7

Instead of adding the acid and the clay separately, it is possible to treat the clay with the acid preliminarily and then add the acid-treated clay to the fatty acids. For this purpose a mixture of fatty acids containing 55% palmitic and 45% stearic acids, and having $3 \times 10^{-3}\%$ of copper, was treated with a bleaching clay upon which

had been absorbed 28% by weight of phosphoric acid. A sufficient quantity of this clay was employed to introduce the quantities of phosphoric acid indicated in the following table. The results obtained are indicated in the table:

	Percent H ₃ PO ₄ Used	Percent Copper
10	0.17	2.2×10^{-4}
	0.33	4.9×10^{-4}
	0.5	3.0×10^{-4}
	0.75	6.6×10^{-4}
	1.0	6.6×10^{-4}

15 No mineral acid remained in any of these samples. It is evident from this table that the quantity of metals removed does not materially change once a certain minimum quantity of acid has been employed.

I claim as my invention:

1. Process of removing a metal selected from the group consisting of nickel and copper, said metal being present at least partially in the form of soaps, from saturated fatty acids containing the same, which comprises treating the fatty acids in a molten condition with from 0.1 to 1% by weight of a concentrated strong mineral acid in the presence of sufficient bleaching earth to adsorb said acid and separating the bleaching earth and the adsorbed acid from the fatty acids to leave the saturated fatty acid substantially free from mineral acid.
2. Process of removing a metal selected from the group consisting of copper and nickel, said metal being present at least partially in the form of soaps, from saturated fatty acids containing the same, which comprises treating the fatty acids in a molten condition with from 0.1 to 1% by weight of a concentrated strong mineral acid in the presence of approximately 2% by weight of a bleaching earth, and separating the bleaching earth and the strong mineral acid adsorbed thereon to leave the fatty acid substantially free from mineral acid.
3. Process according to claim 2 in which the mineral acid is phosphoric acid.
4. Process according to claim 2 in which the bleaching earth is a montmorillonite clay.
5. Process of removing a metal selected from the group consisting of copper and nickel, said metal being present at least partially in the form of soaps, from saturated fatty acids containing the same, which comprises treating the fatty acids in a liquid condition with approximately 0.5% by weight of concentrated phosphoric acid in the presence of approximately 2% by weight of montmorillonite clay and separating the montmorillonite clay with the phosphoric acid adsorbed thereon from the fatty acids to leave the fatty acid substantially free from phosphoric acid.
6. Process according to claim 2 in which the bleaching earth is an acid activated montmorillonite clay.
